UNITED STATES PATENT OFFICE

CHARLES A. KOHL, OF ST. LOUIS, MISSOURI, ASSIGNOR TO ST. LOUIS BUTCHER'S SUPPLY CO., OF ST. LOUIS, MISSOURI, A CORPORATION OF MISSOURI

APPARATUS FOR AND METHOD OF REFRIGERATION

Application filed October 15, 1925. Serial No. 62,523.

My invention relates to improvements in apparatus for and method of refrigeration, and has for its primary object an apparatus designed for use in display or container refrigerators, which will not alone provide refrigeration for said refrigerator but will also automatically create a circulation of cold air therethrough.

A further object is to construct an apparatus for cooling a display container or refrigerator, which will be operated periodically and automatically so as to maintain the refrigerator at substantially a constant temperature and during such cooling cause a forced circulation of air within the refrigerator and simultaneously supply the air thus circulated with sufficient moisture to prevent the drying out of articles stored therein.

A still further object is the method of refrigeration wherein the refrigerator will be properly chilled, the air circulated, and the presence of excess moisture or excess dryness in the refrigerator be eliminated whereby sogginess of meats or similar food products stored is eliminated or excessive loss due to absorption from said articles by the air is prevented.

In the drawings:

Fig. 1 is a longitudinal section of a display refrigerator or container with my apparatus located therein, and connected up ready for operation;

Fig. 2 is a fragmental longitudinal vertical section showing a modified form of apparatus;

Fig. 3 is a vertical longitudinal section of a display refrigerator showing still another form of apparatus;

Fig. 4 is a horizontal section taken on the line 4—4 of Fig. 3; and

Fig. 5 is a modified form of supply nozzle employed.

In the construction of my device, I employ a display refrigerator or container having a chilling chamber 6 and a display chamber 7. The refrigerator is provided with a double bottom 8 on which rests a container 9. This container extends into the display chamber and is designed to be filled

with a non-freezing liquid, such as brine or similar substance. That portion of the container 9 within the display chamber is provided with a lid 10. Located on the lid 10 is insulating material 11, such as cork or the like. This may cover the entire lid 10 or may only partially cover it as illustrated in Fig. 1.

Separating the display and refrigerating chambers is a wall 12, the lower portion of which is provided with openings 13. These openings are formed by slitting the material and bending it outward as illustrated in Figs. 1, 2 and 3. The wall 12 is spaced apart from the top of the refrigerator so as to form a passageway 14, which will permit the circulation of air. Extending beneath the pan 9 and preferably between the two walls comprising the floor 8 is a pipe 15, its end 16 extending into the container 9. The opposite end of the pipe 15 is connected to a pump 17, which may be either of the rotary, centrifugal or reciprocating type. To the outlet of the pump 17 is a pipe 18, which extends into the chilling chamber 6 and has secured on its end a spray nozzle 19. The pump 17 is driven by an electric motor 20, which also drives a compressor 21 in which the condenser constitutes the housing, there being several refrigerating machines now on the market which employ the housing or casing as a condenser and therefore the construction of the compressor will not be described in detail as the peculiar construction thereof is not essential to my device. Attached to the compressor is a refrigerating coil 22, which is located in the chilling chamber 6. The motor 21 is controlled by means of a thermostat 23, which is located at any convenient point in either the chilling or display chambers. By means of this thermostat the temperature within the refrigerator can be controlled.

It will be noted from Figs. 1, 2 and 3 that the construction of the openings through the wall 12 are such that when water is sprayed through the nozzle 19, it will not enter the display chamber but be directed downward into the container 9. In Fig. 2 I have shown a modified form of construc-

tion in which the refrigerating or expanding coil 24 is located within a container 25. This container is provided with a cap 26, which closes a filling opening 27 so that the 5 container can be filled with a non-freezing solution. This non-freezing solution will entirely surround the coil 24. In Fig. 3 I have shown still another modified form of device in which the refrigerating or expanding coil 28 is located in the container 9, thus 10 leaving the chilling chamber 6 practically unobstructed and clear. The container 9 may be either the full width of both the display and chilling chambers, or it may be 15 the full width of the chilling chamber but have that portion, which extends into the display chamber, reduced in width as illustrated in Fig. 4. This construction is optional and depends a great deal on the amount of refrigeration desired for the particular refrigerator in which it is to be used.

The operation of my device is as follows: The container 9 is filled with a non-freezing solution, such as brine or the like, and the 25 proper refrigerant supplied to the compressor. The device is now ready for operation. The motor 21 is started and in so doing the compressor 21 and pump 17 placed in operation simultaneously. The compressor works 30 in the usual way, forcing the refrigerant through the coils where it expands and chills the same. The pump being in operation pumps the non-freezing solution from the container 9 and discharges it through the 35 nozzle 19 in the form of a high speed, very fine spray. This spray strikes either the coil in Fig. 1 or the container 25 in Fig. 2 and flows over the same and cuts off all accumulation of frost, and at the same time, the 40 speed, at which this liquid rushes through the air, creates a suction in the upper portion of the chilling chamber 6 and a compression in the lower portion. This compression escapes through the openings 13 45 and flows along the lower part of the display chamber while the upper portion or strata of air flows through the opening 14 into the chilling chamber where it is driven downward, cooled by the coil and also by the 50 cold non-freezing solution, and again passed into the display chamber.

The insulation 11 is placed on top of the lid 10 for the purpose of preventing the air within the display chamber from coming 55 in contact with the lid because on account of the excessive cold in the container 9, any moisture in the air would congeal on the lid and form frost. This frost would in time act as an insulator and prevent the cold 60 from reaching the box properly as well as making an extremely moist box. It is also for the purpose of removing frost that the spray is used because it is a well known fact among refrigerating engineers that a very 65 heavy accumulation of frost around refriger-

erating pipes diminishes their efficiency. In fact in packing houses it has been found necessary to install a double refrigerating system and use one for a certain period of time and then use the other, thereby allowing frost to be removed from the pipes whereas in smaller plants it is frequently necessary in order to get sufficient refrigeration to have a man chop off the frost which has accumulated on the pipes.

My structure eliminates entirely all this accumulation of frost and consequently the refrigerating plant is always up to its capacity in refrigeration but, as before mentioned, the spray not alone keeps down and prevents this accumulation of frost, but it also causes a rapid circulation of cold air through the refrigerator and entirely eliminates the siphon system now relied on in chilling refrigerators.

In Fig. 5 I have shown a modified type of nozzle in which the pipe 18 is connected to a cross pipe 29. From this pipe extend a plurality of pipes 30, which are provided with perforations through which the non-freezing solution is forced at high speed in the form of a spray.

Another feature of my device is the circulation of the non-freezing liquid in the container 9, it being taken from one end and after being chilled is returned to the opposite end of the container, therefore this non-freezing solution does not rise in temperature to any appreciable extent and by its circulation the entire refrigerator has the cold non-freezing solution pass from one end to the other, and therefore the refrigerator is cooled much more quickly and evenly throughout than is possible where the non-freezing solution is located in one end or in the center of the container.

Another important feature of my device is that it can be placed anywhere within a building because no drain pipes are necessary. This has been found to be a great drawback because most stores at the present time are equipped with concrete floors and the owners of the building object very much to having holes for drain pipes punched through these floors. Furthermore it frequently happens, especially in butcher shops, that there is no cellar below the store and consequently no drain can be installed without tearing up the floor. This in many instances will not be permitted by the owners, or, if permitted, can only be done at the expense of the person renting the store. My device entirely eliminates the necessity of these drains.

While I have shown one type of thermostat in Fig. 1 I do not desire to limit myself to this precise construction as there are many thermostats on the market at the present time, which can be used and which are so constructed as to operate between certain

degrees of temperature and automatically make an electric connection, and it is by the use of any of these well known commercial types of thermostats that my device can be made to operate automatically. In other words, the temperature of the refrigerator can be maintained substantially constant. However in place of the thermostat, if it is desired, an ordinary thermometer can be placed within the refrigerator and the ordinary switch used to place the compressor in operation.

I do not desire to limit myself to the precise construction shown in the drawings, as it may be desirable to place all of the operating mechanism within the refrigerator and again I may construct a refrigerator with a display chamber on each side of the refrigerating chamber or I may place a refrigerating chamber at each end of the display chamber without departing from the spirit of my invention, and I may again build a separate compartment to enclose the pump, motor and compressor and utilize the top surface of the compartment as a counter. All of these variations fall within the scope of my invention and, as before mentioned, I do not therefore desire to be limited to the precise construction shown in the drawings; the important features of my device being the circulation of the non-freezing solution, the artificial forced circulation of air, and the prevention of frost accumulation on the refrigerating coil.

Having fully described my invention, what I claim is:

1. An apparatus for refrigeration comprising a refrigerator having a chilling and a display chamber arranged side by side, said chambers communicating with each other at their top and bottom, a nondraining container located beneath said chambers, a nonfreezing solution located in said container, a refrigerating coil located in said chilling chamber, means adjacent the refrigerator for supplying a refrigerant to said coil, and means for circulating and forcibly spraying said nonfreezing solution downwardly over said coil whereby the nonfreezing solution is cooled and air in the refrigerator drawn from the top of the display chamber into the chilling chamber, cooled and discharged into the display chamber at its bottom by the nonfreezing solution.

2. An apparatus for refrigeration comprising a refrigerator having a chilling and a storage chamber arranged side by side, a vertical wall having passages therethrough adjacent its top and bottom located between said chambers, a container located in the bottom of said refrigerator and extending below said wall, a nonfreezing solution in said container, means for removing some of said solution from said container and forcing it through the chilling chamber in a

downwardly directed diverging spray whereby air in the storage chamber is drawn from the top thereof into the top of the chilling chamber, cooled by the spray and returned to the storage chamber at its bottom, and means located in said chilling chamber for chilling said solution as it is sprayed, said chilling means also providing additional cooling for the circulating air.

3. An apparatus for refrigeration comprising a refrigerator having a chilling chamber and a storage chamber adjacent and communicating with each other at their top and bottom, a refrigerating coil located in said chilling chamber, a combined compressor and condenser connected to said coil, a container located in said refrigerator and below said chambers, a nonfreezing solution located in said container, a suction pipe connected to said container at a point remote from said chilling chamber, a pump connected to said suction pipe, a discharge pipe connected to said pump, a downwardly directed spray nozzle connected to said discharge pipe and located in the chilling chamber above said coil, means for operating said pump and compressor simultaneously whereby a portion of the nonfreezing solution is withdrawn from said container and is forcibly and downwardly sprayed over said coil in the chilling chamber and returned to the container, said spray adapted to draw air into the chilling chamber from the top of the storage chamber and discharge it into the storage chamber at its bottom, said sprayed solution and liquid being simultaneously chilled when passing said refrigerating coil, and means for preventing the spray from entering the storage chamber at its bottom.

4. A device of the class described comprising a refrigerator having a chilling chamber and a storage chamber, a vertical wall having openings therethrough at its top and bottom located between said chambers, a refrigerating coil located in said chilling chamber, a combined compressor and condenser connected to said coil, a container located in the refrigerator and extending under said wall, a nonfreezing solution located in said container, a suction pipe connected to said container at a point remote from said chilling chamber, a pump connected to said suction pipe, a discharge pipe connected to said pump, a spray nozzle carried by said discharge pipe and located within the chilling chamber above said coil, means for operating said pump and compressor simultaneously whereby the nonfreezing solution is withdrawn from the container and forcibly sprayed downwardly into the chilling chamber and over the coil whereby said solution is chilled, said forcible spraying causing the air in the chilling chamber and in the storage chamber to circ-

culate and become cooled by contact with the air and the refrigerating coil, and means for placing the pump and compressor in and out of operation automatically as the temperature in the refrigerator varies.

5. An apparatus for refrigeration comprising a display chamber, a brine receptacle located beneath the display chamber and separated therefrom, a chilling chamber vertically disposed adjacent said display chamber and communicating with the display chamber at its upper and lower ends and communicating with said brine receptacle, means for forcibly discharging cold liquid in said chilling chamber and comprising a conduit in communication with the brine receptacle at a point remote from said chilling chamber, a pump and a downwardly directed spray nozzle, and a chilling coil located in said chilling chamber beneath and spaced apart from the spray nozzle and in the path of the descending spray issuing from said nozzle.

6. In a device of the class described a container having a display chamber, a chilling chamber adjacent one end of said display chamber, said chambers communicating with each other at their top and bottom, a nonfreezing solution container located beneath said chambers and open to the chilling chamber only, a nonfreezing solution located in said solution container, a pump for withdrawing said solution from said solution container, a spray nozzle vertically disposed in said chilling chamber, a conduit connected to said pump and nozzle whereby solution withdrawn from the solution container is sprayed downwardly through the chilling chamber and returned to the solution container, said spray adapted to draw air from the top of the display chamber into the chilling chamber and discharge it therefrom into the bottom of the display chamber, and a refrigerating coil located within the chilling chamber in the path of said spray whereby said spray and the air circulated thereby are simultaneously chilled.

7. The combination with a cooling chamber, of means for retaining a pool of cooled secondary refrigerant in said chamber pipe coils for a primary refrigerant in said chamber, and means for withdrawing said cooled secondary refrigerant from said pool and spraying it into contact with the air in said chamber and then into contact with said coils.

In testimony whereof I have affixed my signature:

CHARLES A. KOHL.
